UNITED STATES PATENT OFFICE.

JOHN F. BERNIK, OF PITTSBURGH, PENNSYLVANIA.

TABLE.

Specification of Letters Patent. Patented Dec. 16, 1919.

1,325,390.

Application filed July 30, 1918. Serial No. 247,433.

To all whom it may concern:

Be it known that I, JOHN F. BERNIK, a citizen of the United States, residing at Pittsburgh, in the county of Allegheny and State of Pennsylvania, have invented new and useful Improvements in Tables, of which the following is a specification.

The object of the invention is to provide a table structure capable of yielding vertically and laterally to compensate for jars or shocks while capable of maintaining a substantially stable equilibrium, and to this end the same consists in a construction, combination and arrangement of parts hereinabove set forth, it being understood that changes in form, proportion and details may be resorted to within the scope of the claim without departing from the spirit of the invention.

20 In the drawing:—

Figure 1 is a side view of a table constructed in accordance with the invention.

Fig. 2 is a sectional view of the upper or platform portion of the same.

25 Fig. 3 is an inverted plan view of a portion of the platform to show the attached securing plate.

Fig. 4 is a detail view showing the means for securing the supporting spring to the 30 base ring.

Fig. 5 is a bottom plan view of the disk which is attached to the table platform.

The table embodying the invention consists essentially of a base 10 preferably in 35 the form of a ring which is adapted to be secured as at 11 by screws or otherwise to the floor, and seated thereon is a spiral spring 12 of a sufficient gage to support the table platform 13 with the load for which 40 it is designed. As shown, the spring which is broad at its base, is tapered upwardly to

its point of attachment to the platform, the means whereby the lower coil of the same is secured to the base ring consisting of staples 14 or the equivalent thereof. Similar fastening means 15 are employed to attach the upper coil of the spring to a disk 16 which in turn is secured to a fastening plate 17 permanently attached to the under surface of the platform by means of screws, nails or 50 the equivalent thereof, as shown at 18. The disk 16 is secured to the plate 17 by means of screws 19, and said disk is provided with a sleeve 20 which extends upwardly into an opening 21 in the plate 17 and is interiorly 55 threaded for the reception of a threaded tongue 22 on a counter weight 23 which depends within the coils of the spiral spring and serves as a means for steadyng the table and maintaining it in its proper supporting position.

It will be understood that while a table constructed as described will yield to slight jars, and shocks, the vibrations for example of the floor will be absorbed by spring 65 support, and at the same time the likelihood of injury as by breaking of the table top or platform from its supports or pedestal as by applying an unusual weight to one side thereof will be reduced to the minimum.

70 What is claimed is:—

A table having a base, a spiral spring having its bottom coil attached to said base, a disk secured to the uppermost coil of said spring, a table top or platform secured to 75 the disk, the latter being provided with a central threaded socket engaging the top or platform, and a counterbalancing weight having a tongue threaded into said socket.

80 In testimony whereof I affix my signature.

JOHN F. BERNIK.
